UNITED STATES PATENT OFFICE.

JAMES A. BURNS, OF ATLANTA, GEORGIA.

ICE-CREAM FREEZER.

SPECIFICATION forming part of Letters Patent No. 431,645, dated July 8, 1890.

Application filed July 6, 1889. Serial No. 316,705. (No model.)

To all whom it may concern:

Be it known that I, JAMES A. BURNS, a citizen of the United States, and a resident of Atlanta, in the county of Fulton and State of Georgia, have invented certain new and useful Improvements in Ice-Cream Freezers; and I do hereby declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to apparatus for the freezing of cream, ices, &c., and has more particular reference to the class of ice-cream freezers in which as the material becomes frozen it is automatically delivered from the 20 machine.

The object of this invention is to bring this class of devices to better and cheaper construction and to a greater degree of effectiveness in operation, and to so arrange the several parts that they will be conveniently detached for the purpose of repairing, replacing, and cleansing, the details of construction necessary for these purposes being hereinafter fully set forth and claimed.

30 In the accompanying drawings, Figure 1 is a central vertical section of the device, the revolving cylinder not being in section. Fig. 2 is an end elevation of the device from the left-hand end of Fig. 1, with the cover removed, exhibiting the parts therein shown from that direction. Fig. 3 is a face view of the crank and hollow journal, showing the novel means for attaching the crank and sealing the opening in the hollow journal to prevent the escape of the refrigerant. Fig. 4 is an edge view of the parts shown in Fig. 3. Fig. 5 is an enlarged view of the scraping device, looking outward from the interior of the machine, such view being a side elevation of said scraper. Fig. 6 is a longitudinal vertical sectional view of the cylinder, showing the interior arrangement of the parts. Fig. 7 is an enlarged vertical sectional view of the scraper, showing its preferable construction and the relative positions of the scraping-edge, the guide, and the cylinder. Fig. 8 is a side view of the hollow journals, showing the in-

clines upon which the lips or projections on the cover are forced to make a water-tight joint between the said journal and the cover. Fig. 55 9 is a face view of the hollow journal, showing the packing against which the packing abuts.

In the figures, like reference-marks indicating corresponding parts, A is the non-conducting casing, which surrounds the operative parts of the device, and B is the cylinder, which is journaled in said casing in such a manner as to revolve freely. In the interior of the casing A, and supported by the pan C', 65 which rests on the bottom of the casing, is the receiving-pan C, which is filled, when desired, through the funnel D on the outer side of said casing and connecting with the interior. In the side of the casing, and preferably in the 70 side opposite to the funnel, is an aperture, and in this aperture is placed the scraper E, in such a manner that it will scrape the surface of the cylinder as it revolves.

All of the preceding details will be more 75 fully and explicitly described hereinafter.

The casing A may be made of any suitable material, and in case any material not a non-conductor or a poor conductor of heat be used it would be advisable to insulate it by any of 80 the well-known means for such purposes. This casing is preferably of a size and form about as shown in Figs. 1 and 2, and preferably has cleats on its bottom to prevent the warping thereof, said cleats also forming 85 incidentally legs on which the machine rests. This casing is preferably formed in two sections—an upper one a and a lower one a'—which are fastened together by dowel-pins inserted in one section and entering holes in 90 corresponding positions in the other section, and the whole held together by two or more hooks attached to one section and engaging or clasping over pins or other convenient appliances for holding the two parts together. 95 These sections may also be held together by hinges, applied at the left-hand end preferably, and hooks or other convenient appliances at the other end. This form is preferably used for convenience in placing in position 100 and removing the interior parts of the machine.

Resting on and supported by the bottom of the casing A is the pan C', which is to con-

tain the insulating or cooling material used to cool and keep cool the contents of the pan C, which is supported, preferably, by the pan C', and which is to receive and hold the cream 5 or other material to be frozen in such a manner that the cylinder revolving on the material thus presented to it may be able to take it all up during the process of freezing it. The pan C', when used for the purpose of 10 holding the insulating or cooling material, is partly filled with this material, and the pan is set into it and the other parts of the machine then put in place, and the operation of freezing the liquid is begun in the usual way.

15 When the liquid to be frozen contains egg, corn - starch, or other non-conducting substance, it is desirable to use an insulating and cooling material which will reduce the temperature of the contents of the pan C nearly 20 to the freezing-point. When this is done, congelation readily takes place when the cylinder B is charged with the refrigerant and rotated in the material to be frozen, as contemplated and provided for in the construction 25 and use of the machine. When the liquid to be frozen does not require previous cooling in this way, then the insulating or cooling material can be omitted from pan C' without interfering with the operation of the machine. Through the side of the casing, near 30 the top of the said pan, a hole is made, in which is inserted tube d of the funnel D. This funnel is preferably constructed with one side oval and the other flat, and to the flat side is attached the tube d, which forms 35 the passage from the funnel D to the interior of the casing A when the funnel is in place. In the side of the casing to which the funnel D is attached, when in use, and near the top 40 thereof and the said funnel, are placed the pins d', which prevent the funnel from turning sidewise and wasting its contents. These pins d' are placed at a slight distance from the sides of the funnel to allow a little space 45 in which the funnel may be partially rotated sidewise to aid in removing it from the casing when desired.

It is through the funnel that the material to be frozen is supplied to the pan C from 50 the outside of the casing, which, it will be seen, is readily and easily done without removing the cover, thereby obviating the necessity of removing the cover to fill the pan, and in this way admitting warm air and 55 impairing the economical use, as well as the efficiency of the machine.

The cylinder B, which is hereinafter described in detail, is, as before stated, journaled in the sides of the casing A, and is turned in 60 the direction indicated by the arrow in Fig. 1. It is obvious that when this cylinder filled with the refrigerant is revolved on its axis through the liquid material in the pan C a film of this liquid will become sufficiently 65 gealed to adhere to the surface of the cylinder, and during its passage from the pan C to the scraper E it will become frozen sufficiently

for the purposes for which it is intended, and therefore it will be necessary to add to the parts already mentioned a device to remove 70 this frozen material for use. For this purpose the scraper E, Figs. 1, 5, and especially 7, of novel and advantageous construction, has been supplied. This scraper consists of a flat piece of metal e, preferably bent up at the sides 75 to prevent the material sliding down the plate of the scraper from escaping at the sides. The upper edge of the said plate e is preferably, though not necessarily, turned slightly toward the cylinder to facilitate its scraping off the 80 frozen material and to slightly stiffen the edge of the said plate, so as to prevent it from springing. This plate or scraper e is elastically held in contact with the cylinder B by the springs 85 e', of wire or flat steel or other material suited to the purpose, which springs or other appliances for the purpose are soldered at their top ends to the said plate, and their bottom ends are inserted into the side of the casing A, as shown, the thin metal plate a'' being 90 preferably supplied to strengthen the same, and while the plate a'' is obviously not absolutely necessary to the operation of the device, yet it is considered desirable, as it will prevent the lateral enlargement of the holes 95 to such an extent as to materially reduce the pressure of the springs. The holes in the casing A, in which these springs are inserted, are vented inwardly, preferably, to allow any liquid which may get into them to escape, 100 and thus prevent the swelling of the cover and the partial closing of the holes.

To the under side of the scraper E is attached in any desirable manner a guide e'', consisting of a thin flange or a bar or a piece 105 of metal of any other convenient form, which projects therefrom a sufficient distance to touch and bear against the cylinder as soon as the cutting or scraping edge of the scraper is close to or just in contact with the surface 110 of the cylinder, and thus prevent the scraper from bearing too forcibly against the surface of the cylinder, and thereby abrading its surface and injuring it. The object of this guide is to provide for easy and effective automatic 115 adjustment of the cutting or scraping edge of the cylinder, and thereby prevent the scraper from unduly scraping or abrading its surface by coming in too forcible contact 120 with it in consequence of the pressure exerted by the springs or the resistance of the frozen material to the action of the scraper, or the inequalities in the surface caused by 125 defects in construction, or other causes rendering such automatic adjustment necessary.

When in use, the surface of the cylinder is sufficiently lubricated by the thin film of the material to be frozen which is left by the scraper when in proper adjustment to prevent any injurious abrasion of the surface 130 by the cutting or scraping edge of the scraper or the guide e''. Consequently this guide e'' is a very important, if not absolutely necessary one, for aiding the scraper in the per-

formance of its function, and materially prolonging the life of the cylinder by preventing its injurious abrasion by the scraper. Further, the thin film of frozen or congealed material left on the surface of the cylinder by the combined action of the scraping-edge and the guide e'' , as before mentioned, assists in congealing more of the material to be frozen in its passage through the unfrozen material in accordance with well-known physical laws governing the congelation of liquids.

The cylinder B is constructed of sheet metal, preferably of tin of good thickness, and has on one end the journal b, and in the other is a hole, over which is fastened in any convenient manner, preferably by riveting and soldering, the hollow journal b', Figs. 1, 2, 3, 4, and 8, in the latter of which figures one of the inclined planes b''', cut into the periphery of the flange around the outer end of said journal, is shown most clearly. There are two of these inclined planes, preferably on opposite sides of the said flange, and the cover b'', to which is attached, preferably integral therewith, the hand-crank b''', having two lips b'''' thereon, which engage with and are forced up these inclined planes b'''. This hand-crank in use exerts force in a direction that will press the cover b'' securely over the opening in the mouth or outer end of the journal b' and make, by compressing the rubber gasket b'''' or other soft packing, a water-tight joint therein, which prevents the escape of any of the refrigerating mixture.

On the interior of the cylinder are placed the buckets F, which carry the refrigerating compound to the top of the cylinder and allow it to fall back, thus keeping its ingredients thoroughly mixed, and thereby securing

the maximum effect of the refrigerant at the 40 surface of the cylinder, which comes in contact with the material to be frozen, which is not the case in freezers of this class as ordinarily constructed. These buckets may be of any number and of any general form desired, the object being, as just described, to carry the refrigerating material in contact with the surface of the cylinder through a portion of its revolution, and then to allow it to fall and become mixed with the other portions, which are in turn taken up and carried partly around, as before described.

Having thus described my invention, what I claim as new, and desire to secure by Letters Patent of the United States, is—

1. In an ice-cream freezer, the combination of the freezing-cylinder supported by hollow journals within the casing A, the pans C C', arranged one within the other to receive the cream to be frozen by the cylinder passing 60 through the same, the funnel D for supplying the cream to said pans, and the scraper for removing the frozen cream from the cylinder, consisting of a piece of sheet metal bent up at its sides to form a trough and provided with 65 springs e and bearing-plate e'' , substantially as shown and described.

2. In an ice-cream freezer, the scraper E, formed of a piece of sheet metal bent up at its sides to form a trough and provided with 70 the spring e' and bearing-plate e'' , substantially as shown and described.

In testimony whereof I hereunto affix my signature in presence of two witnesses.

JAMES A. BURNS.
